UNITED STATES PATENT OFFICE.

EDWARD S. MORGAN, OF DUBLIN, ASSIGNOR OF ONE-HALF TO JAMES MCNEILL AND SILAS O. LEESON, OF RICHMOND, INDIANA.

WIRE-FENCE MACHINE.

SPECIFICATION forming part of Letters Patent No. 432,951, dated July 22, 1890.

Application filed April 1, 1890. Serial No. 346,202. (No model.)

To all whom it may concern:

Be it known that I, EDWARD S. MORGAN, a citizen of the United States, residing at Dublin, in the county of Wayne and State of Indiana, have invented certain new and useful Improvements in Wire-Fence Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 of the drawings is a perspective view. Fig. 2 is a vertical transverse section. Fig. 3 is a vertical longitudinal section. Fig. 4 is a sectional detail, and Fig. 5 is a perspective detail, view. Fig. 6 is a broken detail perspective view more fully disclosing the construction of the bent pitman *e'*, as also portions of the carriages and shaft.

This invention relates to certain improvements in fence-machines; and it consists of the novel construction and combination of parts, as will appear from the following description and accompanying drawings.

In the drawings, A refers to a suitable upright support, upon which is arranged the operative mechanism.

30 B B are series of carriages or reels, each series consisting of two carriages provided with spindles *a a*, carrying spools of wire, and with needles *b*, through which the wire is passed, those of a series being arranged opposite to each other and only a short distance apart. Each carriage B is connected to a plate or bracket *c*, arranged upon the inside of the support A by means of a cross-piece *c'*, passing through a slot *d*, extending almost the 40 entire length or height of the support.

In the slot *d*, at equal intervals apart corresponding to the distances the horizontal wires or stringers are arranged apart, are secured disks or plates C, which are each provided with a central aperture *c²* for the passage of the shaft therethrough. These disks or plates are also each provided with notches or recesses *c³*, one arranged in its upper edge and one in its lower edge, to receive and limit 45 the movement of the cross-piece *c'* of each

carriage. The brackets or plates *c* are connected, the upper ones to a slide D by a bent pitman *e* and the lower ones to a similar slide D' by similar pitman *e'*, said slides being arranged and guided in their movements by 55 keepers or staples *f*, secured to the supports A.

The carriages of each series are provided at their meeting edges with recesses or notches *g*, which receive and embrace the rectangular portions *g'* of the shafts E, passing through 60 the slot *d* in the support A. These shafts E are driven by intergearing pinions *h*, mounted thereon and driven by beveled gear-wheels *i*, geared together, one of said wheels being mounted or secured on the shaft of one of 65 said pinions and the other secured on a shaft *i'*, suitably journaled on the support A and having a handle *j*'. The shafts F are hollow or tubular to permit the passage therethrough of the horizontal wires or stringers of the 70 fence, around or upon which the crossing-wires of the fence are woven, as presently seen. The slides D D' are connected together by a handled lever D, fulcrumed upon a bar 75 *d'*, secured upon the support A.

In operation it will be seen that the machine being in position upon the horizontal wires or stringers, as shown in Fig. 1, and it is desired to continue the diamond-like weaving of the crossing-wires or web portion, the 80 same as shown at the left of the machine, the handle of the lever D² is depressed, which will throw each series of two carriages to the next horizontal wires. Before this, however, the machine is moved bodily the requisite interval along said horizontal wires. The handle of the driving-shaft of the gearing is now 85 grasped and turned, which will revolve the carriages and cause the coiling of the wires carried by the spools on said carriages around 90 the horizontal wires, and thus effect the weaving of the wires, as aforesaid. By again moving the machine and reversing the movement of the lever shifting the position of the carriages, the aforesaid operation of weaving 95 the wires is repeated, and in this manner the fence is woven throughout.

Having described this invention, what I claim is—

1. In a fence-machine, the carriages carry-

ing wire-holding spools and needles, in combination with intergeared shafts, each engaging a pair of carriages and driven by suitable gearing, and means for shifting said carriages 5 from one point to another and alternately into engagement with the adjacent pairs of shafts, substantially as set forth.

2. In a fence-machine, the carriages or reels carrying wire-holding spools and needles, oppositely movable slides connected together by a handle-lever, the bent pitmen connecting together said carriages or reels and said slides, the support having a longitudinal slot,

along or in which are arranged at intervals disks or plates provided with central apertures and in their opposite edges with notches or recesses, and the hollow shafts engaging opposite reels or carriages of a series and bearing intergearing pinions suitably driven, substantially as set forth. 15

In testimony whereof I affix my signature in presence of two witnesses.

EDWARD S. MORGAN.
